UNITED STATES PATENT OFFICE.

JAMES E. MUSTARD, OF GLEN HALL, INDIANA.

BUTTER FOR GRAIN-BINDERS.

SPECIFICATION forming part of Letters Patent No. 635,967, dated October 31, 1899.

Application filed June 7, 1898. Serial No. 682,825. (No model.)

To all whom it may concern:

Be it known that I, JAMES E. MUSTARD, a citizen of the United States, residing at Glen Hall, in the county of Tippecanoe and State of Indiana, have invented certain new and useful Improvements in Butters for Grain-Binders, of which the following is a specification.

In self-binding reaping-machines it is necessary, in order that the bundles shall be tied at the proper point, at or near the centers thereof, notwithstanding that the straws of the grain are of different lengths, that a device or apparatus known as a "butter" shall be employed, which device consists, generally speaking, of a swinging plate adapted to be moved in and out over one side of the deck of the binder and which serves to guide the butt-ends of the grain-straws to a predetermined point a certain distance from the binding mechanism. With shorter grain-straws this plate is moved farther in, nearer the center of the deck and binding mechanism, and with long grain-straws is moved farther out, nearer the margin of the deck. Such a butter is necessarily provided with means for causing the butt-ends of the grain-straws to move along its surface and progress down the deck as rapidly as do the tops, as in the absence of such mechanism the inclined surface of the plate would retard the grain-straws and throw them out of line.

My present invention relates mainly to this straw-butt-propelling mechanism, the means of operating the same, and its relation to the axial line of the supports for the butter, whereby it is permitted its swinging movement.

An apparatus embodying my said invention will be first fully described and the novel features thereof then pointed out in the claims.

Referring to the accompanying drawings, which are made a part hereof and on which similar letters and numerals of reference indicate similar parts, Figure 1 is a perspective view of a self-binding reaping-machine provided with a straw-butter embodying my present invention; Fig. 2, a side elevation of such a butter and the adjacent portions of the self-binding reaping-machine; Fig. 3, a top or plan view of the parts shown in Fig. 2 as seen from the dotted line 3.3 in Fig. 2, the overhanging top plate or shield of the butter being removed

to show the parts beneath; Fig. 4, a side elevation of the butter on an enlarged scale; Fig. 5, a horizontal sectional view of the same as seen from the dotted line 5.5 in Fig. 4, and Fig. 6 a view of the inner side of the butter and adjacent parts as seen when the machine is turned around from the dotted line 6.6 in Fig. 3.

The machine shown in Fig. 1 and partially in Figs. 2, 3, and 6 is, generally speaking, a self-binding reaping-machine of a well-known type. This machine, except the butter and its operating mechanism, which form a part thereof, is not of my present invention, and therefore will not be further described herein except incidentally and so far as appears necessary to give a clear understanding of my said invention. It is provided with the usual elevator-belts or raddles E E', by which the grain is conveyed from the platform, where it is deposited after being cut, up to the deck D of the machine, where it is bound into bundles. One of the rollers R which carry the belt E has a bevel-pinion p upon its end, which engages with a corresponding pinion 1 on the shaft which drives the butter mechanism. This shaft 2 is mounted in a sleeve-like bearing 3, which latter is secured in any appropriate manner to the frame F of the self-binding reaping-machine, at the upper part thereof, near the end of the shaft of the roll R. This bearing is shown as having an arm 4, and a rod or bar 5 is mounted in this arm 85 and in an ear 6, which ear is also carried by the frame of the machine. Said rod or bar 5 is bent over and extends back and thence downwardly, so that its extreme end is in line with the shaft 2, but above and free from the 90 said shaft, as best shown in Fig. 4.

The main plate P of the butter has two arms 7 and 8, one of which is pivoted upon the shaft 2 and the other upon the portion of the rod which is in line with said shaft. By 95 this arrangement it will be seen that as this main plate is adjusted back and forth on the deck D its relation to the shaft 2 is not changed, the axial lines of said shaft and of its supports being coincident.

The main plate P carries any required number of pivoted devices adapted to force the butts of the straw down along its face, which devices I have denominated "kickers." I

have shown in the present instance three of these kickers 9, 10, and 11. These kickers are mounted upon pivots 12, 13, and 14, respectively, in suitable bearing-bars 15 and 16, secured to the outer side of the main plate P. The kicker 9 has an arm 17 extending out from the pivot-point, and a pitman 18 connects this arm to the crank on the upper end of the shaft 2. It is obvious, therefore, that as the shaft 2 revolves, the arm 17, and through it the kicker 9, will be rocked on the pivot 12 and the point of said kicker projected through the orifice provided therefor in the plate P to the inside of said plate, so as to move above and over the deck D of the reaping-machine. A connecting-rod connects the arm 17 to an arm 20 on the kicker 10, and a corresponding connecting-rod 21 connects said arm 17 to an arm 22 on the kicker 11. As will be observed, the arm 20 extends in the opposite direction from the arms 17 and 22, so that as the kickers 9 and 11 are projected the kicker 10 is withdrawn, and vice versa. Any desired number of these kickers can be employed by making similar or suitable connections. As will be noticed by an inspection of the drawings, especially Fig. 5, the form of these kickers is such that they are not only adapted to force the butts of the grain somewhat away from the inner surface of the main plate P of the butter, but also to move it down the face of said plate and down the deck D toward the point where the grain is discharged from the machine.

As will be seen especially by an examination of Figs. 2 and 3, the butter is enabled to be given any desired position by means of a handle 23, which is pivoted to the main plate P and is adapted to engage with a suitable (preferably forked) detent 24 on a cross-bar b on the machine, the bar 23 being notched or serrated, as shown in Fig. 2, for the purpose of conveniently securing it at such point as may be desired.

The hood H, which is usually provided in machines of this character above the deck D, is cut away somewhat, as best shown in Fig. 3, in order to give the butter room for movement, and this is compensated for in the apparatus shown by a shield S, attached to the upper side of the main plate P and which extends over the edge of said hood.

Having thus fully described my said invention, what I claim as new, and desire to secure by Letters Patent, is—

55

1. The combination, in a grain-binder, of a butter comprising a pivoted main plate adapted to swing over the deck of the machine and having suitable perforations therethrough, kickers pivoted on the outside of said plate and adapted to operate through said perforations, a crank-shaft for operating said kickers, suitable connections between said crank-shaft and kickers, said crank-shaft being journaled in a bearing on the side of the frame, and geared to a driving-shaft, and said swinging plate being hinged at one side on said shaft and at its other side on a pivot secured on the frame in line with said shaft, all substantially as set forth.

70

2. The combination, with a self-binding reaping-machine, of a butter composed of a pivoted main plate adapted to swing over the deck of the machine and a series of "kickers" pivoted in suitable bearings on the outer side of said main plate with their operating ends extending through suitable orifices in said plate, a crank-shaft, a pitman extending from said crank-shaft, arms on the kickers and connecting-rods connecting the several arms, substantially as set forth.

75

3. The combination, in a butter for a grain-binder, of a series of kickers pivotally mounted on the main plate of said butter with their operative ends extending through perforations in said main plate, pivots to said kickers carried by suitable bearings upon the outside of said main plate, arms on each of said kickers, said arms extending alternately in different directions, connecting-rods connecting said several arms, and mechanism whereby the whole is simultaneously put in motion, said several kickers being thereby operated to move oppositely or in different directions from each other, substantially as set forth.

85

In witness whereof I have hereunto set my hand and seal, at Glen Hall, Indiana, this 1st day of June, A. D. 1898.

JAMES E. MUSTARD. [L. S.]
